Walter Wisbrun
By Frank S. Asherman,
Atty.

The foot arch support consists of the flat central plate 1. This is adapted to the strong central part of the tendinous sheet 2 of the sole of the foot and is bordered at the forward end 5 by a second smaller surface 3 bent down about a straight line and terminating in a line running parallel to this, which surface 3 bears on the fat cushion 4 of the forepart of the foot behind the joint capitula 5. The central plate 1 terminates 10 at the rear end at the apex line E—E which is directed transversely to the longitudinal axis of the foot and corresponds to the front termination of the fat cushion 6 of the heel. At this 15 apex line E—E, the central plate merges into a downwardly bent rear surface 7 which serves as a support for the front rising part of the heel cushion 6.

This form of construction of the foot arch support is suitable both for the production of loose 20 inserts and for building into orthopaedic boots.

I claim:

1. A foot arch support comprising a metal plate having three surfaces disposed angularly with respect to each other, namely, a central transversely horizontal plane surface inclined downwardly from the rear towards the front and determined in position and extent by the highest point of the curvature of the foot, which is located in front of the heel, and the end of the first and fifth metatarsal bones close behind the joint capitula or sesamoid bones, a front surface bent downwardly about a straight line at the forward end of the central surface and terminating in a line running parallel thereto, so that it

applies itself to the channel of the fat cushion at the forepart of the foot behind the joint capitula, and a rear surface bent downwardly about the horizontal line at the anterior end of the fatty cushion of the heel to serve as a support for the anterior ascending part of said cushion of the heel.

2. A foot support formed by a plate having only three foot supporting surfaces, the middle part of said plate being flat in crosswise and longitudinal directions, the end portions of the plate forming small flat surfaces inclined downwardly.

3. A foot arch support comprising a metal plate having three surfaces disposed angularly with respect to each other, namely, a central transversely horizontal plane surface inclined downwardly from the rear towards the front and determined in position and extent by the highest point of the curvature of the foot, which is located in front of the heel, and the end of the first and fifth metatarsal bones close behind the joint capitula or sesamoid bones, a front surface bent downwardly about a straight line at the forward end of the central surface and terminating in a line running parallel thereto, so that it applies itself to the channel of the fat cushion at the forepart of the foot behind the joint capitula, and a rear surface bent downwardly about the horizontal line at the anterior end of the fatty cushion of the heel in order to serve as support for the anterior ascending part of said cushion of the heel, said plate tapering in width from front to rear with the widest part forward.

WALTER WISBRUN.
